UNITED STATES PATENT OFFICE

GEORGE ALEXANDER LONG, OF HARTFORD, CONNECTICUT, ASSIGNOR TO THE LONG SECURITY LOCK COMPANY, OF HARTFORD, CONNECTICUT, A CORPORATION OF CONNECTICUT

LOCK

Application filed July 3, 1929. Serial No. 375,643.

My invention relates to that class of key operated locks that are employed to secure the doors or other closures of compartments of various kinds, my improved lock being particularly applicable in connection with the doors of safe deposit boxes and similar compartments found in banks and other depositories, and an object of my invention, among others, is the production of a lock in which the mechanism may be readily changed to prevent its operation by a key formerly employed in the lock, and to so safeguard such operation as to prevent any surreptitious or unauthorized change or changes from being made.

One form of a lock embodying my invention, and in the construction and use of which the objects herein set out, as well as others, may be attained, is illustrated in the accompanying drawings in which—

Figure 1 is a face view of my improved lock showing a two-part key inserted and in its initial position, but with such key cut off on a plane denoted by the dotted line 1—1 of Figure 2.

Figure 2 is a side view showing the key in the initial position as in Figure 1.

Figure 3 is a rear view.

Figure 4 is a view similar to Figure 1 but showing the two-part key turned to its unlocking position.

Figure 5 is a view similar to Figure 4, but showing one of the key members removed.

Figure 6 is an edge view of the lock showing one key member in its unlocking position in the key center and the other key member inserted through the back face of the lock to release the key center for positioning for a change of keys.

Figure 7 is a rear view showing the parts in the position of Figures 5 and 6, the key being cut off near the case.

Figure 8 is a front view of the lock showing the key center in position to permit removal of the key member projecting from the front of the case and to permit insertion of a differently bitted key member thereby to effect a change in tumbler combination.

Figure 9 is a rear view with the parts in

the same position as in Figure 8, the key being cut off.

Figure 10 is a front view of the lock with the front face plate removed, the parts being in normal locking condition.

Figure 11 is a similar view, but with the parts in unlocked condition, but with one key member omitted.

Figure 12 is another similar view showing the parts in released condition for a change of key member.

Figure 13 is a view in lengthwise section on a plane denoted by the dotted line 13—13 of Figure 10 with both key members in position to unlock the lock.

Figure 14 is a similar view of a portion of the lock substantially on a plane denoted by the dotted line 14—14 of Figure 12, but with one key member inserted into the back of the lock and the mechanism released thereby to permit a change of key combination.

This invention relates more particularly, as hereinbefore stated, to means for changing the tumblers so that they may be operated by different keys, the present invention, in fact, being an improvement on that illustrated and described in my co-pending application filed November 18, 1927, of Serial Number 234,257, the lock mechanism being substantially the same in both instances and the difference residing mainly in the devices for holding the members while a change is being effected. For this reason a brief description only of the lock mechanism, as such, is given herein.

In the accompanying drawings the numeral 15 denotes the case of my improved lock, that may be of ordinary form, with a plug or key center 16 therein having a key opening or slot 17 for the reception of a key. This plug or key center is rotatably mounted and extends into an escutcheon 18 on the face of the lock. A set of holes for the members 19 of a set of pin tumblers is formed in the key center, said members acting in connection with another set 20 of pin tumblers to release the key center under the action of a proper key and permit said center to be rotated. The members 20 are located in a block 21 secured within the key case,

said block having a circular recess to permit rotation of the plug or key center. These tumblers will be actuated or positioned by notches on one edge of a key in a manner common to locks of this type.

The opposite edge of said key is properly notched to engage and position leaf tumblers 22 pivotally mounted in the case and having notches in their ends to register with and receive fingers 23 projecting from a set of guards 24 slidably mounted in the case upon a locking bolt 25.

When the key is inserted to its proper position in the key center the notches on one edge will position the pin tumblers 19 and 20 so that the line of division between them will register with the wall 26 of the recess in the block 21 hereinbefore referred to. This will release the key center so that it may be rotated by force applied to the key, and in this rotation the angular notches on the opposite edge of the key will engage the tumblers 22 and position them, as shown in Figure 11, so that the notches in the ends thereof will register with the fingers 23. After such positioning of the leaf tumblers, and in the rotation of the plug or key center, a lug 27 on said center will engage a notch 28 in the edge of the bolt, thereby moving the bolt backwardly, entering the fingers 23 within the notches in the leaf tumblers and releasing the door or other device to which the lock is attached, this position of the lock members being shown in Figure 11 of the drawings.

All of the parts thus far described will be found in my co-pending application hereinbefore mentioned, and therefore, of themselves, form no part of the present invention. I have also shown a two-part key, and while this, of itself, is made the subject matter of other applications filed by me, it is also made use of in connection with mechanism now to be described to carry the present invention into effect.

This two-part key comprises a plug controlling member 29 and a bolt controlling member 30 which for convenience of description may be termed respectively custodian and owner parts, the former being retained by the custodian of the compartment or box and the latter being retained by the owner or lessee of such compartment or box. These two key parts may be removably united in any suitable manner, but in such way as to permit removal of one part while the other part is retained in the lock.

My improved lock comprises two notches 31 oppositely arranged in the edge of the escutcheon 18 to receive the extreme opposite edges of two key parts or members. This permits insertion of the key to a point to locate retaining notches 32 near the inner end of the blade of each key member opposite a retaining lip 33 forming the bounding

edge of the hole into the end of the escutcheon. This location of the key positions the pin tumblers 19-20 to enable the plug 16 to be turned in a clockwise direction, with the mechanism as arranged herein. Such turning movement will operate the leaf tumblers 22, and the parts cooperating therewith, and the bolt 25 will be withdrawn in a manner as hereinbefore described.

A support 35 for a stop 36, in the form of a tooth projecting from the support, is movably mounted in a recess in that edge of the block 21 opposite the tumblers 20. This support is yieldingly mounted as by means of stems 37 seated against springs located in holes extending from the bottom of the recess in the block 21, said springs being retained by a cap covering the holes and the springs thereby holding the support in its normal position, and as shown in Fig. 10 of the drawings.

When the key center or plug 16 has been turned to locate the bolt 25 in its unlocked position, as just described, a tumbler retaining rib 38 in which the tumblers 19 are located on said plug is moved into contact with the stop 36, as shown in Fig. 11, and further rotation of the key center in this direction is prevented. In this position the key parts are located as shown in Fig. 4, in which position the plug controlling part 29 of the key is located opposite a releasing notch 39 in the escutcheon. In this position of the parts the key opening or groove in the plug 16 will register with a receiving notch 40 for the plug controlling member or key in the rear face of the lock, as shown in Fig. 7. The plug controlling part 29 of the key may now be removed from the lock, this construction, as hereinbefore remarked, being such as to enable it to be separated from its companion member 30. If now inserted in an opening 41 in the rear face of the lock (see Fig. 7 of the drawings) and through the notch 40 in the edge of said opening, this key member

will encounter the pin tumblers and move one or more of them against the support 35, moving said support inwardly against the tension of its springs and moving the stop 36 from the path of movement of the rib 38 so that the latter may be moved further in the same direction as that of unlocking movement thereof. The key member 29 is now used to thus rotate the plug a slight distance further in the said direction and until said member 29 is opposite a releasing notch 42 for said member in the rear of the face of the lock case and as shown in Figure 9.

This final rotation of the plug in an unlocking direction places the key member 30 in registering position with a notch 43 in the edge of the hole into the escutcheon, so that said member 30 may be removed from the plug. Another key member, of the same general characteristics but differently

- notched or bitted, may now be inserted through the notch 43, and as shown in Fig. 8 of the drawings. When the key member 30 is located in to the final position shown in 5 Fig. 12 its bits will cease to act upon the leaf tumblers 22 and the latter will be returned by their springs to their normal positions, as shown in said figure, and the fingers 23 of the guards 24 will move the latter so that 10 said guards together with the fingers will be arranged in line. In this position of the parts the key member 30 may be readily withdrawn from the key center or plug without obstruction by the leaf tumblers.
- 15 A key member differently bitted being now inserted in the plug and turned backwardly the leaf tumblers will be caused to assume relative positions determined by bits on the key member, and the relative locations of the 20 guards 24 will be changed accordingly, and before engagement of the notches in the edges of the guards with a blade 45 projecting from the edge of the chamber in the case (see Figs. 10 to 12), which blade maintains 25 the guards in their relative positions during the time that the fingers 23 are disengaged from the notches in the leaf tumblers. It will be understood that the steps or bits in the edges of different key members are all 30 so formed that one of the notches in the edge of each guard will always be in line to receive the blade 45. When the plug is thus moved backwardly as just described the rounded edge of the rib 38 will encounter 35 the tumblers 20 and depress them to permit such backward movement.
- It is thus seen, from the foregoing description, that the two-part key is employed to unlock the lock, and that the key member 29 40 in the possession of the custodian is used to place the plug in position to permit removal of the key member 30 when the leaf tumblers are engaged with the guards. This therefore will be done only with the knowledge 45 edge of the custodian and any unauthorized person is therefore prevented from making the change. When the leaf tumblers and guards are thus engaged the insertion of a differently bitted key, and the turning of said 50 key backwardly to its normal position, will change the positions of the leaf tumblers and of the guards to accord with the bits on said key, and the latter may thereafter be used to operate the lock mechanism until another 55 change in the leaf tumbler combination is made.
- I claim—
1. A lock mechanism including a key receiving member adapted to receive a two-part key, tumblers adapted to be positioned by both parts of said key in said member to control operations of the lock mechanism, means operated by one part of said key to permit excess movement of said key receiving member to a tumbler changing position, and 60 means to permit insertion of a new key part in said key receiving member when in said position.
2. A lock mechanism including a key receiving member adapted to receive a two-part key, tumblers adapted to be positioned by both parts of said key in said member to control operations of the lock mechanism, a lock case in which said mechanism is located, means operated by one part of said key insertable through the back of said case to permit excess movement of said key receiving member to a tumbler changing position, and means to permit insertion of a new key part in said key receiving member through 70 the front of the case.
3. A lock mechanism including a key receiving member, tumblers adapted to be positioned by a key in said member to control operations of the lock mechanism, means operated by a key in said key receiving member to permit excess movement of said member to a tumbler changing position, and means to permit insertion of a key in said member when in said position.
4. A lock mechanism including a key receiving member, tumblers adapted to be positioned by a key in said member to control operations of the lock mechanism, a case within which said mechanism is located, key means insertable in said key center through an opening in the rear of the case to effect excess movement of said key receiving member to a tumbler changing position, and means to permit insertion of a key in said member when in said position.
5. A lock mechanism including a key receiving member operable by a two-part key having its parts separably connected and insertable in said member, tumblers adapted to be positioned by one of the key parts to control operations of the lock mechanism, means operated by the other key part after separation from the first mentioned key part to effect excess movement of said key receiving member to a tumbler changing position, and means to permit removal and insertion of a key part of the first mentioned type in said member when in said position.
6. A lock mechanism including a key receiving member operable by a two-part key having its parts separably connected and insertable in said member, tumblers adapted to be positioned by one of said key parts to control operations of the lock mechanism, a case in which said mechanism is located, means operated by the other key part after separation from the first mentioned key part inserted through an opening in the rear of the case to effect excess movement of said key receiving member to a tumbler changing position, and means to permit insertion of a key part of the first mentioned type in said member through the front of the case when in said tumbler changing position.

7. A lock mechanism including a key receiving member, operable by a two-part key having its parts separably connected and insertable in said member, tumblers adapted to be positioned by a key part in said member to control operations of the lock mechanism, means operative by a key part after separation from the first mentioned key part in said member to effect excess movement of said key receiving member to a tumbler changing position, and means to permit insertion of a key part of the first mentioned type in said key receiving member when in said position.

8. A lock mechanism including a key receiving member operable by a two-part key having its parts separably connected and insertable in said member, tumblers adapted to be positioned by a key part in said member to control operations of the lock mechanism, a lock case in which said mechanism is located, means operable by a key part after separation from the first mentioned key part in said key receiving member through the rear of the case to permit excess movement of said key receiving member to a tumbler changing position, and means to permit insertion of a key part of the first mentioned type in said key receiving member when in said position.

9. A lock mechanism including a key receiving member adapted to receive a two-part key, tumblers adapted to be positioned by both parts of said key in said member to control operations of the lock mechanism, a stop movably mounted to limit operation of said key receiving member in normal locking and unlocking operations of the lock mechanism, means operable by one part of said key to remove said stop from the path of said key receiving member to permit positioning of the latter for a tumbler changing operation, and means to permit insertion of a new key part in said member when in said position.

10. A lock mechanism including a key receiving member adapted to receive a two-part key, tumblers adapted to be positioned by both parts of said key in said member to control operations of the lock mechanism, a movably mounted support, a stop on said support located in the path of movement of said key receiving member in normal locking and unlocking operations of the lock mechanism, means operable by one part of said key to move said support and said stop from the path of said key receiving member to permit the latter to be positioned for a tumbler changing combination, and means to permit insertion of a new key part in said key receiving member when in said position.

11. A lock mechanism including a key receiving member having pin tumblers therein, other tumblers adapted to be positioned by a key in said member to control operations of the lock mechanism, a support movably mounted, a stop located on said support, the latter being located for movement by said pin

tumblers when the key center is in one position to remove the stop from the path of said key receiving member to permit the latter to be positioned for a changing tumbler combination, and means to permit insertion of a key in said key receiving member when in said position.

12. A lock mechanism including a key receiving member, pin tumblers located in said member to be positioned by a key therein, other tumblers operable by said key to control operations of the lock mechanism, a support, a stop located on said support in the path of movement of said member in the normal locking and unlocking operations of the lock, means to permit insertion of a key in said key center to effect excess movement of said pin tumblers to operate said support to remove said stop from the path of movement of said member for excess movement of said key receiving member to a tumbler changing position, and means to permit insertion of a key in said key receiving member when in said position.

13. A lock mechanism including a key receiving member, pin tumblers located in said member, a two-part key insertable in said member, other tumblers adapted to be positioned by a key in said member to control operations of the lock mechanism, a case within which said mechanism is located, a movably mounted support, a stop on said support located in the path of said key receiving member to limit its movement in normal locking and unlocking operations, means to permit insertion of one of said key parts in said member to move a pin tumbler against said support and thereby remove the stop from the path of said key receiving member but retain it in the path of movement of a pin tumbler, and means to permit insertion of a key in said key receiving member when in said position.

14. A lock including a key receiving member adapted to receive through one end thereof both parts of a two-part key and through the other end only one of said parts, tumbler lock mechanism operated by both parts of said key when jointly received through one end of said member, and means operated by the one part of the key when received through the second mentioned end of said member to permit change of the tumbler setting of said mechanism.

15. A tumbler type of lock mechanism including a key receiving member movable between predetermined limits for normal locking and unlocking operations of the tumbler mechanism and to a position beyond one of said limits for changing the tumbler setting of said mechanism, and means operated by a device positioned in said key receiving member to permit movement of said member to said tumbler setting changing position.

16. A tumbler type of lock mechanism including a key receiving member movable be-

tween predetermined limits for normal locking and unlocking operations of the tumbler mechanism and to a position beyond one of said limits for changing the tumbler setting
5 of said mechanism, a movable stop for limiting the normal movement of said member in one direction, and means positioned in said key receiving member for moving said stop to permit the member to be moved to said tumbler setting changing position.

10 17. A tumbler type of lock mechanism including a key receiving member movable between predetermined limits for normal locking and unlocking operations of the tumbler mechanism, and to a position beyond one of said limits for changing the tumbler setting of said mechanism, a movable stop for limiting the normal movement of said member in one direction, said stop being
15 movable to permit movement of the key receiving member into said tumbler setting changing position by actuation of certain of the tumblers of said mechanism, and means in said key receiving member formed
20 to receive a key for actuating said last mentioned tumblers.

25 18. A lock mechanism including a key receiving member, a set of tumblers in said member operable by a key to control normal movement of said member and to permit its movement to an excessive degree to permit removal of a key from said member to be replaced by another key, and a set of bolt controlling tumblers to be operated by said last
30 mentioned key.

35 19. A lock mechanism including a key receiving member operable by a two-part key having its parts separately connected and inserted in said member, tumblers adapted
40 to be positioned by one of the key parts to control operations of the lock mechanism, means operated by the other key part retained in said member after separation from the first mentioned key part to effect excessive movement of said key receiving member to a tumbler changing position, means for preventing removal of said other key part until said member has been placed in its key changing position, and means to permit
45 removal and insertion of a key part of the first mentioned type in said member when in said position.

50 GEORGE ALEXANDER LONG.
